TOY VEHICLE

Filed Sept. 27, 1935

abreast of the foot resting on the platform in substantial alinement with the steering post. Such will permit easy propulsion of the toy, having all the advantages of the well known "scooter" toy without any of the disadvantages thereof, as for example easy tilting of the toy, and to which the scooter toy is susceptible; and in addition will have an advantage over the other known type of toy generally referred to as a "coaster" in that in the latter type of toy the propelling foot is at the rear of the toy. It will therefore be appreciated that the main feature of the present invention is the provision of the opening at approximately the center of the platform of the toy for accommodating the propelling foot, it being through the medium of this opening that a safety toy of this character is provided, that is to say a toy which is not likely to tilt either when moving in a straight path or incidental to a steering of the toy either to the right or to the left.

Further the toy of this invention being formed substantially completely of wood can be cheaply and economically constructed and can be used by a child indoors, it being primarily intended for children of tender age due to the lightness in weight of the toy.

Having thus described my invention what is claimed as new is:—

A toy of the character described comprising a substantially U-shaped broad flat platform, supporting rollers for the platform mounted in opposite sides of the U adjacent the open end of the U, said platform at the closed end of the U being provided with a circular opening, a bearing block secured to the platform and bridging said circular opening, a steering post journaled in the bearing block, and rollers mounted on the lower end of the steering post and movable toward the right or left within the confine of the circular opening.

EDWIN F. SILKMAN.
